BUILDING WALL OF HOLLOW BLOCKS

Frank B. Cheney, Alamosa, Colo.

Application October 16, 1943, Serial No. 506,471

3 Claims. (Cl. 72—41)

1

This invention relates to building walls and blocks therefor, and more particularly to walls and blocks made of concrete, cinder concrete, or the like, which have desirable insulating properties.

Concrete building blocks have heretofore been provided with one or more apertures extending vertically therethrough, for lessening the weight of the block. Such blocks are normally placed in rows or tiers, with the blocks of one row in staggered relation with respect to the blocks of each adjacent row. However, when there are two vertical apertures through the block, as is the usual case, there are a plurality of vertical apertures extending substantially the height of the wall, which permit considerable circulation of air upwardly and/or downwardly of the wall. Also, there is considerable transfer of heat through the concrete blocks, which is to be expected, since the apertures in the blocks are provided merely to lessen the amount of material used rather than provide desirable insulating qualities.

There have also been attempts to utilize hollow core pieces, entirely surrounded by cementitious or other material, but again this is done for lightness in weight, and not to provide desirable insulating qualities.

Among the objects of this invention are to provide a building block which is light in weight and therefore requires a minimum amount of material, yet is highly effective as an insulator; to provide such a block which prevents movement or circulation of air through hollow spaces in a wall, when a plurality of such blocks are utilized in constructing the wall; to provide such a block which is composed partially of relatively light and cheap material, such as cardboard or the like; to provide such a block which may utilize a cardboard box, which is very cheap and easily procured, as a component part thereof; to provide a building wall formed of such blocks, wherein the tendency for heat to be transferred from the inside to the outside of the wall, or vice versa, is considerably reduced; to provide a wall in which blocks of the above character are utilized; and to provide a building block of the above character, which is relatively simple in construction and easy to handle. Other objects and the novel features of this invention will become apparent from the following description.

A building wall constructed in accordance with this invention may comprise a plurality of blocks, each consisting of an inner insulating box completely enclosing a dead air space, and the top, bottom, sides and ends of which are of corrugated or multi-layer construction in which a double thickness of material is separated by a convoluted or corrugated thickness of material which provides a plurality of dead air spaces within the walls of the box itself. This inner box is composed of relatively light material, such as cardboard or the like, and is exposed on the top and bottom. Extending along the two opposite sides

2

and the ends of the box is a wall of relatively strong material, such as concrete or the like, which takes the load imposed upon the wall. Each end wall of concrete, connecting the two side walls, assists in holding the block together and also functions as a load-carrying element. Such blocks may be placed in a building wall and constructed in accordance with this invention, as set forth in the more detailed description which follows, taken in connection with the accompanying drawing, in which:

Fig. 1 is a side elevation of a wall formed of light weight blocks having desirable insulating qualities, each constructed in accordance with this invention; and

Fig. 2 is a cross section of a block constructed in accordance with this invention, taken along line 2—2 of Fig. 1.

Fig. 3 is a cross section of a block constructed in accordance with this invention taken along the line 3—3 of Fig. 1.

As illustrated in the drawing, a building wall may be constructed of a plurality of blocks B, each of which embodies this invention. Each block B may comprise an inner insulating box 10 formed of relatively light material, such as cardboard, plywood, plastic, or the like, and an outer wall 11 of relatively strong material, preferably extending along two sides and the ends of the inner box. As used herein and in the appended claims "relatively strong" material refers to material which is relatively strong in resistance to compression stresses, the preferred material being wet-poured concrete, though other suitable materials, such as cinder concrete, clay, or the like may be used. Preferably, the relatively strong material is such that it may be poured or formed about the two sides and ends of the inner box, and become bonded to the same. Although the above materials are relatively weak in resistance to tension and shear stresses, it will be understood that materials which are relatively strong in resistance to tension and/or shear stresses in addition to being relatively strong in resistance to compression stresses, may be utilized.

The inner box 10 forms a dead air space 12 in the interior thereof which acts to retard heat transfer through the block and wall. To further increase the retardation of heat transfer, the top 13, bottom 14, ends 15 and sides 16 of the inner box are preferably constructed so as to provide a plurality of dead air spaces 17 by consisting of an outer thickness 18 and inner thickness 19 of material, with a corrugated or similarly convoluted thickness 20 of material interposed therebetween. Such corrugated wall construction of the inner box not only greatly enhances the insulating properties of the block, but also strengthens the inner box, and thus minimizes the tendency for the box to collapse when concrete or the like is poured around the box in forming the block. The fact that the top 13 and bottom 14 of the

box preferably is not contacted by the concrete or the like further minimizes any tendency for the box to collapse during pouring, since a pouring form may be utilized on which the bottom 14 rests. Another part of the form may extend over all or a portion of the top 13, to hold the box more securely in position during pouring. Of course, if desired, the block may be poured from the end, with one end of box 10 spaced from the bottom of the form, and the top and bottom of the box against two opposite sides of the form. Again, the form may be disposed at an angle, for readier pouring. Since the inner box is relatively light, it may be found desirable to utilize a suitable pin, brace or other means for holding the box in place during pouring, in case there is any tendency for the box to float to the top of the material being poured, or otherwise become displaced. When the poured material is concrete, such brace may be removed when the concrete is partially set and the hole thereby left filled with fresh concrete, if it does not fill naturally.

The blocks constructed in the above manner may be utilized in a number of different ways to form a wall. Preferably, the blocks are placed in rows or tiers, as in Fig. 1, with the blocks of one row disposed in staggered relation with respect to the blocks of an adjacent row, both above and below. Mortar 20 is placed along the tops of the concrete side walls, and between the ends of the side walls. No mortar is placed between the concrete end walls of adjacent blocks, or at the top or bottom of the end walls. The mortar between the ends of the concrete side walls causes an insulating space 21 to be formed between the concrete end walls 11 of adjacent blocks in the same row, while the mortar between the tops and bottoms of the concrete side walls causes an air space to be provided between the inner boxes of adjacent blocks in rows above and below each other.

The advantages of the above described building wall and block therefor are numerous and varied. The inner box reduces the weight of material used to a minimum, which reduction in weight is of particular benefit when the wall is supported upon beams or the like and the load of a ceiling, roof or the like is carried by supporting members, such as I-beams, as in skyscrapers or certain types of mill construction. The completely enclosed dead air space within each block not only reduces the amount of heat transferred through the blocks, but also prevents any circulation of air through the wall composed of such blocks. The end walls of relatively strong material, which are preferably made as thin as is consistent with the block holding together during handling and construction of the wall, permits a minimum amount of heat to be transferred through the block. This is of some importance, since the coefficient of heat transfer through the relatively strong material is normally, of course, much greater than the coefficient of heat transfer through the inner box. There is little opportunity for heat to be transferred upwardly or downwardly from block to block, since the end walls of such block are disposed centrally of the insulating corrugated top or bottom of the inner box of the block above and below. Also, air spaces 21 between the end walls, and air spaces between the rows of blocks provide a further insulating effect, but are relatively thin, being only the thickness of the mortar between the blocks, and thus provide little opportunity for air currents to flow between the blocks. This is particularly true of vertical air currents, 75

since in the staggered relation of the blocks in the preferred construction, there are no vertical passages extending the height of the wall.

Relatively light weight blocks are easier to handle, and a wall formed of such blocks may be constructed faster and with less fatigue to workmen. In addition, since a considerable portion of the cross sectional area of the blocks is taken up by dead air spaces, the blocks are wider than if the inner box were not provided, and a wall formed of such blocks is more stable, due to the increased footage and base area of the wall itself and of each component block.

A block constructed with two end walls of concrete or the like is relatively strong, since there is a continuous rectangular ring of concrete or the like all the way around the inner insulating box. However, particularly in instances where the blocks are not subject to much handling, it may be desirable to utilize only one end wall of concrete, thus further reducing the weight and improving the insulating properties. It will be understood, therefore, that a block having only one end wall of concrete is within the scope of this invention.

Although the building wall and block of this invention have been described as composed of certain materials, it will be understood that materials other than those mentioned may be utilized; that the form and shape of the block may be varied within wide ranges; and that other changes may be made without departing from the spirit and scope of this invention, as defined in the appended claims.

What is claimed is:

1. A building wall comprising a plurality of blocks disposed in horizontal rows with the blocks of one row in staggered relation to the blocks of an adjacent row, each of said blocks having two spaced side walls interconnected with two spaced end walls of cementitious material to form an enclosure, a closed six-sided box structure formed of material providing dead air spaces interiorly thereof disposed within said enclosure having four sides in supported contact with said walls and having the additional top and bottom sides disposed within the limits of said walls, said box structure enclosing a major dead air space within the said six walls, and a body of mortar disposed between adjacent side walls of the blocks to provide additional dead air spaces between adjacent top and bottom sides of said six-sided structure.

2. A building wall according to claim 1 wherein said box structure is formed of material having minor enclosed dead air spaces within the bounding surfaces of said material.

3. A building wall substantially as directed in claim 1 wherein said box structure is formed of corrugated cardboard.
